US0D1111527S

(12) **United States Design Patent** (10) **Patent No.:** **US D1,111,527 S**
(45) **Date of Patent:** **** Feb. 10, 2026**

(54) **CRIB**

(71) Applicant: **CHINA WONDERLAND NURSERYGOODS CO., LTD.,**
Guangdong (CN)

(72) Inventor: **Mingpeng Li**, Guangdong (CN)

(73) Assignee: **CHINA WONDERLAND NURSERYGOODS CO., LTD.,**
Guangdong (CN)

(**) Term: **15 Years**

(21) Appl. No.: **29/951,958**

(22) Filed: **Jul. 12, 2024**

(30) **Foreign Application Priority Data**

Jan. 16, 2024 (CN) 202430028397.X

(51) **LOC (15) Cl.** **06-02**

(52) **U.S. Cl.**

USPC **D6/390**

(58) **Field of Classification Search**

USPC D6/331, 333, 390, 391, 392, 344, 383,
D6/718.26

CPC A47D 9/00; A47D 13/06; A47D 13/061;
A47D 13/063; A47D 7/00; A47D 7/002

(57) **CLAIM**

The ornamental design for a crib, as shown and described.

DESCRIPTION

FIG. 1 is a front, left, and top perspective view of a crib showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top view thereof; and,

FIG. 7 is a bottom view thereof.

The broken (dashed) lines show portions of the crib that form no part of the claimed design.

1 Claim, 7 Drawing Sheets
